R. J. Foster
ATTORNEY.

UNITED STATES PATENT OFFICE.

WILLIAM G. NAISMITH, OF DENVER, COLORADO, ASSIGNOR TO THE DENVER ROCK DRILL MANUFACTURING COMPANY, OF DENVER, COLORADO, A CORPORATION OF DELAWARE.

TOOL RETAINER.

Application filed October 21, 1919, Serial No. 332,191.

The present invention relates to tool retainers, particularly of that type employed on rock drills for holding the steel in the chuck.

5 The primary object is to provide means for effectively maintaining the retainer in its active position with respect to the tool, the holding means permitting the retainer to be moved to an inoperative position.

10 An embodiment of the invention that is at present considered the preferable one, is illustrated in the accompanying drawings, wherein:—

15 Figure 1 is a plan view of the front portion of a rock drill, with the retainer and the novel holding means for the latter in place.

Figure 2 is a perspective view of the same,

Figure 3 is a cross sectional view on the line 3—3 of Figure 1,

20 Figure 4 is a detail sectional view on the line 4—4 of Figure 1.

Similar reference numerals designate corresponding parts in all the figures of the drawings.

25 In the embodiment illustrated, a tool holder 5 is disclosed, of well known type, which is held upon the front end of the barrel 6 by side rods 7. This holder is provided with the usual socket, opening through one end and adapted to loosely receive the rear end 30 of a tool, as 8, having a collar 9 thereon. The front end of the holder 5 is provided with oppositely outstanding ears 10.

35 A tool retaining yoke 11 is employed, having an opening 12 through which the shank of the steel 8 will freely pass, the opening, however, being of less width than the diameter of the collar 9. This yoke is provided with side arms 13 slidably mounted in the ears 10, and capable of pivotal movement 40 therein. The limit of the rearward movement of the arms is determined by stop flanges 14 formed upon the side arms, and adapted to abut against the front sides of the ears 10. The arms project beyond the said ears 10, and located thereon, are coiled springs 15, the front ends of which bear against washers 16 that are abutted against the rear faces of the ears 10. The rear ends 45 of the springs 15 bear against washers 17 that abut against retaining nuts 18 threaded upon the rear ends of the arms 13. The inner or front portions of the nuts, as clearly shown in Figure 4, are reduced to form cy-

lindrical bearing surfaces 19, and on said portions are journaled rollers 20 retained between the bodies of the nuts 18 and the washers 17. The tool holder 5 is provided with outstanding lugs 21, the outer faces of which, as at 22, are concaved, forming seats 55 in which the rollers 20 are adapted to engage.

With this construction, it will be evident that when the yoke 11 is in its operative position, or in other words, embracing the shank of the steel 8 in advance of the collar 9, the rollers 20 will be seated, as shown in Figures 1 and 3. These rollers therefore serve to hold the yoke in its active or operative position. At the same time the yoke 65 can be swung, whereupon the rollers will ride out of the seats 22 and down the inclined under cam faces 23 of the lugs 21, the arms having sufficient spring to permit this movement.

70 From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

75 Having thus fully described my invention, what I claim as new, and desire to secure by Letters Patent, is:—

1. The combination with a tool holder, of a tool retainer including a side arm pivoted and longitudinally slidable on the side of the tool holder and having a swinging portion extending rearwardly beyond the pivot mounting, a spring for resisting the sliding movement of the side arm and an element carried by the tool holder in rear of and spaced from the pivot mounting and detachably engaged by the rearward extension to hold the retainer in its active position with respect to a tool placed in the holder.

2. The combination with a tool holder having a tool-receiving socket in one end, of a tool-retaining yoke having side arms pivotally and slidably mounted on the socket and extending rearwardly beyond their pivot mountings, springs on the arms for resisting their sliding movements, and outstanding projections on the holder in rear of the piv-

- tal mountings that are detachably engaged by the arms to hold the yoke in its active position with respect to a tool placed in the holder.
5. 3. The combination with a tool holder, of a swinging tool retainer slidably mounted thereon, a spring for resisting the sliding movement of the retainer, a roller journaled on the retainer and movable therewith, and
- 10 10 a seat for the peripheral portion of the roller that serves to hold the retainer in a predetermined position.
4. The combination with a tool holder, of a swinging tool retaining yoke having side
- 15 15 arms pivotally and slidably mounted on the holder, springs on the side arms for resisting the sliding movements of the arms, rollers journaled on the side arms and swinging therewith, and seats for the peripheral portions of the rollers to hold the retainer in an active position.
5. The combination with a tool holder, of a swinging tool retainer mounted thereon, a retaining nut for the tool retainer carried
- thereby, and a holding roller for the tool retainer journaled on the nut.
6. The combination with a tool holder, of a swinging tool retainer mounted thereon and capable of sliding movement, a spring resisting said sliding movement, a bearing for the spring including a nut on the tool retainer, and a holding roller for the tool retainer journaled on the nut.
7. The combination with a tool holder having a tool receiving socket in one end and outstanding ears, of a tool-retaining yoke having side arms slidably and pivotally mounted on the ears and projecting rearwardly beyond the same, coiled springs on the side arms, retaining nuts on the rear ends of the side arms having journal portions, rollers on said journal portions, and outstanding lugs on the tool holder adapted to be ridden over by the rollers and to hold the yoke in active position with respect to a tool placed in the socket of the tool holder.

In testimony whereof, I affix my signature.

WILLIAM G. NAISMITH.
